UNITED STATES PATENT OFFICE

2,191,602

VENETIAN BLIND

Harry W. Watts, Maplewood, N. J., assignor to The
Edward J. Hoff Company, Hamilton, Ohio, a
corporation of Ohio

Application June 4, 1936, Serial No. 83,428

1 Claim. (Cl. 156—17)

The invention relates to Venetian blinds and more particularly to such blinds having fabric slats.

As is well known, Venetian blinds are composed of a plurality of long narrow slats supported on the cross-members of woven ladder-tapes and are raised and lowered by cords passing through elongated openings made transversely in the slats.

10 The present invention may be considered in relation to the invention disclosed and claimed in the patent to Harry G. Balthasar, 2,091,579, issued August 31, 1937. In the patent the Venetian blind slat is disclosed as fabricated of a 15 relatively light thin material. The slat has been reinforced along its longitudinal edges by means of metallic strips engaged along these edges, or wire inserted in the hems. Also transverse reinforcement has been provided constituted by 20 grommet plates clinched to the side edge reinforcements. These grommet plates have surrounded the clearance apertures for the elevating cords.

It has been the object of the present inventor 25 to provide lateral reinforcement means for the slat adjacent the clearance openings, which reinforcement means not only prevents buckling of the slat but also provides a marginal reinforcement for the clearance openings and additionally 30 to provide that the reinforcement means are efficiently attached with respect to the longitudinal edge reinforcements without clinching of the transverse reinforcement elements themselves. The present invention therefore provides as a 35 structural embodiment, transverse grommet plates clinched with respect to the clearance openings and in another aspect of the invention, grommet plates which are held in place by the longitudinal edge reinforcement means without 40 clinching.

Other objects and further advantages of the invention will be more fully apparent from a description of the following drawing, in which:

Fig. 1 is an end view of a section of a blind 45 showing the ladder-tape with slats supported by it;

Figs. 2 and 3 are top and bottom views respectively of a portion of one type of slat embodying the invention, Fig. 2 being taken on section 2—2 50 of Fig. 1.

Fig. 4 is a section on the line 4—4 of Fig. 2.

Fig. 5 illustrates a modified detail of construction of the combined bracing member and grommet.

55 Figs. 6 and 7 are top and bottom views respectively of another type of slat embodying the invention; and

Fig. 8 is a section on the line 8—8 of Fig. 6.

Referring to the drawing, Fig. 1, a ladder-tape 10 having the usual cross straps 11 supports 5 the slats 12 of the blind. The tape is fastened at the bottom to the rail 14 to which is secured the end of the lifting cord 15.

Referring to Figs. 2, 3 and 4, the body of the slat 12 is made of rather stiff textile fabric such as is commonly used for window shades, and has hems 16 along the longitudinal edges secured by stitching 17. To provide longitudinal rigidity, stiff spring wire 18 is inserted in the hems.

An elongated opening 20 is provided in the slat, 15 through which the cord 15 passes. As is customary, the cord runs through the slats between the tapes. If any lateral pressure is brought to bear on the slat, tending to buckle it, it occurs at the point of contact with the tapes. By reason of the presence of the cord slot 20, this is also the weakest point of the slat. In order to strengthen the slat and at the same time to provide a reinforcing margin for the slot 20 and smooth edges where the slat contacts the cord, 25 a sheet metal bracing member 21 is secured to the slat. This member is slightly wider than the slot 20 and long enough to be bent around the hems 16 to securely grip them and the wires 18 contained in them. Through the member 21 an opening is made of the same size as the opening 30 in the slat and the marginal metal is clinched as at 22 (Fig. 2) to form a grommet for the slot 20, protecting the fabric against raveling and further supporting the fabric.

In Fig. 5 a modified construction is shown in which, instead of crimping the metal of the bracing member around the slot, the bracing member 21' has an opening cut in it the same size as the slot 20 in the fabric and a separate eyelet 23 is clinched around both the fabric and the bracing member.

Referring to Figs. 6, 7 and 8, an embodiment of the invention applicable to a different type of fabric slat is illustrated. As best shown in Fig. 8, 45 the longitudinal edges of the fabric 30 are made rigid by folding them into metal strips 31, which are drawn disproportionately large for the sake of clarity. The combined bracing member and grommet 32 is secured at its ends within the 50 folds of the strips 31 and is clinched around the fabric as at 33.

While the invention has been disclosed in detail in connection with specific examples, it will be understood that these examples are to be con- 55

strued as illustrative and not by way of limitation. Other modifications are contemplated as within the scope of the invention as defined by the following claim.

5. What is claimed is:

The combination with a fabric Venetian blind slat having stiffening means of folded metal along its longitudinal edges and provided with

openings intermediate its ends for receiving cords, of rigid bracing members extending laterally across the slat and having their ends secured within said stiffening means, said members overlying said openings and being clinched around the edges thereof to serve as grommets.

HARRY W. WATTS.
